UNITED STATES PATENT OFFICE

124,291

DESIGN FOR A MOLDED FIBER LUNCHEON
PLATE

Charles J. Chaplin, South Portland, Maine, assignor to Chaplin Corporation, South Portland, Maine, a corporation of Maine

Application July 20, 1940, Serial No. 93,814

Term of patent 14 years

To all whom it may concern:

Be it known that I, Charles J. Chaplin, a citizen of the United States, residing at South Portland, county of Cumberland, State of Maine, have invented a new, original, and ornamental Design for a Molded Fiber Luncheon Plate, of which the following is a specification, reference being had to the accompanying drawings, forming a part thereof.

Fig. 1 is a bottom plan view of a molded fiber luncheon plate, showing my design, it being un-

derstood that the ornamentation shown is continued throughout the plate.

Fig. 2 shows a half sectional view of my molded fiber luncheon plate on line 2—2 of Fig. 1, and a half side elevational view of my article.

Fig. 3 is a top plan view of my design.

What I claim is:

The ornamental design for a molded fiber luncheon plate, as shown and described.

CHARLES J. CHAPLIN.
